UNITED STATES PATENT OFFICE

FREDERICK WOERZ, OF WEEHAWKEN, NEW JERSEY

SIGN

Application filed March 18, 1929. Serial No. 347,861.

The present invention relates to signs having replaceable letters and numerals and adapted for use particularly for house numbers, door name plates and the like.

The inconvenience of finding house numbers and names appearing on name plates in dark hallways and entrances is common experience and the primary object of the present invention is to provide a house number or name plate device which will be readily visible at all times.

Another object is to provide a device which may be cheaply and easily manufactured and readily applied whenever desired.

With these and other objects in view my invention consists in the novel construction combination and arrangement of elements, as will hereinafter be described and shown in the accompanying drawing which forms part of this specification in which similar reference characters denote corresponding parts and in which:

Fig. 1 is a perspective view of one form of my complete device used as a house number plate;

Fig. 2 is a section along line 2—2 of Fig. 1;

Fig. 3 is a view of one of the removable character elements of my device;

Fig. 4 is a view similar to Fig. 1 with the frame cover partially broken away showing my device used as a name plate;

Fig. 5 is a perspective view of a modified form of my device provided with an expanding frame to accommodate a variable number of characters; and

Fig. 6 is a section along line 6—6 of Fig. 5.

Referring to the drawing and more particularly to Figs. 1-3 inclusive, 10 represents a complete number sign which may be constructed as follows:

11 denotes a base plate of any desired shape and shown in the present embodiment as rectangular. The said plate 11 is formed with a circumferential side wall 11' which may be formed by turning up the edges of said plate at right angles to the bottom face thereof or in any other suitable manner.

Adapted to snugly fit over said side walls 50 is a frame 12 having an L shaped cross sec-

tion for a purpose hereinafter specified. Suitable attaching lugs 13 are mounted on the side walls of said frame, for attaching the assembled device to a wall or step or the like.

In order to make my device adaptable for any house number I provide removable character or numeral plates 14 which fit into said bottom plate 11. The said plates in the present instance comprise strips of metal of rectangular shape and are provided with turned up edges 14' on the two narrower sides of said rectangle. On said strips are applied as by painting the numerals or letters or other characters 15 with a luminescent or radio-active material which is visible in the dark. In order to make said characters equally as visible in the light they may be applied on a dark or black background. The length of said strips is such that they just fit into said plate 11 with the edges 14' frictionally engaging the side walls 11' of said plate.

All the character plates are of the same width, and the base plate and frame 11 and 12 respectively are of such dimensions as to receive a specified number of said characters. For instance the modification of Fig. 1 is adapted for four such character plates.

In order to protect said characters in said sign a transparent cover 16 of sheet glass, sheet mica, celluloid or other suitable material is provided which fits over said letters and is held in place thereover by said frame 12.

In use it is merely necessary to choose the desired reference character plates insert them into said plate 11 and lay the cover 16 thereover and mount the frame 12 onto said last named plate and the sign is ready for use.

In the modification of Fig. 4 I show my device as applied to a name plate 17. The sole differentiating feature is in the dimensions of the various parts, all of which are reduced correspondingly, and instead of numbers for characters, letters are employed.

Now then it may be that a name sign of standard size or a number sign of standard size is not suitable for a particular use because of the length of a name or number.

To provide for such a contingency I have arranged an adjustable frame as follows:

My frame 18 consists of two half sections 19 and 20 respectively, one designed to slidably fit into the other. In the present instance section 19 is slidable in section 20. Section 19 comprises a base 19' formed with integral top and bottom walls 19² and 19³ respectively and an end wall 19⁴ said walls each having a bent over top portion 19⁵. The side walls 19² and 19³ respectively are provided with a beaded guide groove 19⁶ extending substantially the full length thereof, for a purpose hereinafter specified. Suitably attached to said wall 19⁴ are fastening tabs 19⁷.

Section 20 is identical in construction with section 19 with the exception that its dimensions are made sufficiently large that the corresponding elements of section 19 may slide in those of section 20.

The character plates 21 which are adapted to be used with this modification comprise strips of metal or other suitable material of a determined width and a suitable length.

The transversal edges 21' of said strips are first bent forwardly at right angles to said strip and then again bent at angle to the first bend to form lips 21² which are designed to slidably engage said beads 19⁶ and 20⁶ of the section 19 and 20 respectively. The said lips 21² are capable of slight compression in order that the same sized character will fit in both members 19 and 20. The same radioactive or luminescent material forming the characters on a dark background employed with the previous modification is used on said plates.

The member 19 is of such dimensions that it exactly holds a given number of said character plates and in using my device the numeral or character plates are first inserted into said member and then the remainder are inserted into section 20. The section 19 is then pushed into section 20 until the edge 19⁸ thereof rests against the nearest character plate in section 20. This avoids the necessity of having to force the forward edges of members 19² and 19³ over the lips of the plates in member 20.

Any suitable transparent cover 22 as before may be used. The said cover is mounted between the lip 21² and the top portions 19⁵ and 20⁵ of members 19 and 20.

There is frictional engagement between members 19 and 20 sufficient to prevent them from sliding unless actuated by hand.

Various other modifications of my device may be made without departing from the spirit of my invention and I do not wish to be limited to the details shown and described.

What I claim is:

1. An expandible sign composed of two telescopically engaging sections each formed in the upper and lower walls with longitudi-

nally extending grooved beads slidably interengaging one another, individual character plates each formed at its upper and lower ends with resilient lips adapted to slidably engage said grooved beads of either 70 of said sections.

2. An expandible sign composed of two telescopically engaging sections each formed in the upper and lower walls with longitudinally extending grooved beads slidably 75 interengaging one another, individual character plates each formed at its upper and lower ends with resilient lips adapted to slidably engage said grooved beads of either of said sections, and one of said sections having a length which is a multiple of the width of a character plate.

3. An expandible sign comprising two telescopically engaging sections each formed in the upper and lower walls with longitudinally extending grooves slidably interengaging one another, individual character plates on which characters are applied with luminescent paint, said plates each formed at their upper and lower ends with resilient 85 lips adapted to slidably engage said grooves of either of said sections.

Signed at New York this 16th day of March, 1929.
